UNITED STATES PATENT OFFICE

143,531

DESIGN FOR A FISHLINE WEIGHT

Walter J. Harris, Seattle, Wash., assignor to
Pacific Marine Supply Company, Seattle, Wash.

Application March 27, 1945, Serial No. 118,733

Term of patent 14 years

(CL. D31—4)

To all whom it may concern:

Be it known that Walter J. Harris, a citizen of the United States, residing at Seattle, Washington, has invented a new, original, and ornamental Design for a Fish-Line Weight, of which the following is a specification, reference being had to the accompanying drawing forming a part thereof, in which:

Figure 1 is a perspective view of a fish-line weight showing my new design;

Figure 2 is a view in side elevation of the weight shown in Figure 1;

Figure 3 is a front view in elevation; and

Figure 4 is a rear view in elevation of the weight shown in Figure 1.

I claim:

The ornamental design for a fish-line weight, as shown.

WALTER J. HARRIS.
